UNITED STATES PATENT OFFICE.

CHARLES E. MILLER, OF CHICAGO, ILLINOIS, ASSIGNOR, BY MESNE ASSIGNMENTS, TO AMERICAN ARCH COMPANY, OF NEW YORK, N. Y., A CORPORATION OF DELAWARE.

LOCOMOTIVE-FURNACE ARCH.

1,138,044.

Specification of Letters Patent.

Patented May 4, 1915.

Application filed February 7, 1913. Serial No. 746,752.

To all whom it may concern:

Be it known that I, CHARLES E. MILLER, a citizen of the United States, and a resident of Chicago, Cook county, Illinois, have invented certain new and useful Improvements in Locomotive-Furnace Arches, of which the following is a specification.

My invention relates generally to improvements in boiler furnaces of locomotives and has particular reference to improvements in refractory arches of the type adapted for use with furnaces having arch supporting tubes.

The general object of my invention is to improve the construction of such arches to the end that they can be cheaply built, easily installed, and maintained in efficient working order with little attention.

Another object of my invention is to provide a sectional arch for locomotive fire boxes equipped with arch-supporting tubes; which shall be easily adjustable to considerable variations in the widths of the fire box and to irregularities in the arrangement or spacing of the arch supporting tubes, and particularly to irregularity in spacing of the side tubes from the side sheet, to the end that the size and forms of brick required to construct arches in different locomotives can be maintained at a minimum.

My invention consists generally in a locomotive fire box having a group of arch tubes longitudinally arranged therein and spaced throughout the width thereof, in combination with a refractory arch body comprising a plurality of substantial identical bricks resting upon the tubes and laterally coextensive therewith, and side bricks resting upon the outer rows of the arch body and extending upwardly and outwardly into abutment with the side sheets, said side bricks having their lower ends formed in manner to take a plurality of positions upon the side bricks of the body portion, and being thereby adapted to close spaces between the side tubes and the side sheets of greatly varying widths.

My invention also consists in the unique arrangement, construction and co-operation of parts whereby the objects named above and others hereinafter appearing are attained.

My invention will be more readily understood by reference to the accompanying

drawings, forming a part of this specification, and in which:

Figure 1 is a vertical, longitudinal section of a locomotive fire box provided with a refractory front arch embodying my invention; Fig. 2 is an enlarged transverse section substantially on the line 2—2 of Fig. 1; Fig. 3 is a view similar to Fig. 2, but taken on the line 3—3 of Fig. 1; Fig. 4 is a sectional detail showing my arch adapted for use in narrow fire boxes; and Fig. 5 is a perspective view of my unique side or key brick.

It is often desirable and necessary to install arches in different locomotives wherein the arch tubes are evenly spaced, but wherein there is great disparity in the spacing of the side tubes from the side sheets. Also in some instances there is some difference in the relative spacing of the arch tubes themselves. Numerous arches have been constructed which are readily adjustable to irregularities in the spacing of the arch tubes and, while my arch is adapted for use in furnaces wherein the arch tubes are in irregular spaced relation, that is not the primary use for my arch. The variation of the spacing of arch tubes is usually not very great, and it is therefore comparatively easy to provide bricks adjustable to these slight variations. On the other hand, the disparity in the spacing of the side tubes from the side sheets is often very great. I am aware that bricks have been devised for closing spaces of varying widths between the side tubes and the side sheets. These bricks, however, are only adapted to close spaces varying slightly in width. Certain of the bricks hitherto devised are also open to the objection that they do not form positive keys or wedges between the body of the arch and the side sheets, and are therefore liable to work off the body, and fall into the fuel bed.

Other of the side bricks hitherto devised are of such construction that they require peculiarly formed arch body bricks with which to coact. Arches made from such bricks, therefore, require a great many forms of bricks for a single arch and special arrangement or placing of the bricks in the arch itself. The labor required for the installation of arches composed of a great number of brick forms obviously is greater than that required for installing arches composed of

but few brick forms. This is a factor which must be considered in determining the advantages or disadvantages of a locomotive arch. It is often necessary to repair parts of the arch from time to time. In order to accomplish this readily, it is extremely desirable that each brick of the arch be separably detachable without the removal of several of the other bricks for that purpose.

16 I shall now describe in detail my arch which overcomes a great many of the objections which have been urged against arches hitherto devised.

The locomotive fire box here shown is one of the modern wide type fire boxes having the usual flue sheets 2, side sheets 3—3, rear sheets 4, and crown sheet 5. The bottom of the fire box is closed by the grate 6. The flues 7 extend forward from the upper part 20 of the flue sheet and communicate with the smoke box at the front end of the locomotive. The arch tubes 10 extend from the lower part of the flue sheet 2 to the upper part of the rear sheet 4, thus occupying an inclined position, and water flows from the front water leg 9 through to the tubes and into the rear water leg 9" thereby protecting the tubes from burning. It is usual to provide four arch tubes in the wide type of fire box here shown, but it should be understood that the number of tubes varies in the different types of fire boxes, there usually being a smaller number in the narrower type, as will be more fully discussed hereinafter.

While the arch here shown is a front arch, it should be understood that it is adapted for use as a rear arch. The tubes are substantially equally spaced throughout the width 40 of the fire box and the outermost tubes 10' I shall, for facilitating the description and understanding, of the invention, refer to as "side tubes." The tubes 10 and 10' serve to support a plurality of bricks 11. These 45 may have grooved sides which rest upon the tubes, and vertical side edges 12. This form of brick makes a very solid arch body and has no small edges or projections to be knocked off.

50 These bricks are all substantially identical in form and the workman does not therefore have to select a special brick for a particular position in the arch. As before stated, certain of the narrow type fire boxes do not 55 usually require as many arch tubes as the wide type, and certain of the arches hitherto devised which are adapted for wide type fire boxes are not adapted to the narrow type. My arch is not open to this objection, as will 60 be seen by reference to Fig. 4 wherein I have shown my arch installed in a narrow fire box having but three arch tubes. The side bricks 13, for the purpose of closing the spaces between the side tubes and side sheets 65 are also the same for both type of fire boxes

and a description of the brick as used in the wide type fire box will serve for both.

A novel feature of the side brick is that its arch abutment end has a plurality of longitudinal notches providing steps any one 70 of which may be engaged with the edge of the arch body.

The sides of the fire box usually converge at the top and curve into the crown sheet. The arch supporting tubes since they are 75 parallel and extend from the lower part of the flue sheet upwardly to the rear sheet are obviously closer to the side sheets at their upper ends. Therefore, the side portions of the upper part of the arch are closer to the 80 side sheets than the side portions of the lower part of the arch. The spaced relation of the arch tubes from the side sheets at the upper end and at the lower end often varies to such an extent that in arches hitherto devised side or key bricks of two different sizes are necessary for use along a single side of the arch. This is so even with side bricks that are capable of closing spaces of slightly different widths.

90 In Fig. 2 I have shown the bricks closing the relatively smaller spaces at the upper end of the arch. In this instance I place the lower step 15 of the side brick 13 upon the arch body. The brick in this position is 95 ordinarily adapted to close spaces between the side tubes and side sheets of slightly varying distances. For instance the brick in this position may be used for several of the upper rows of the arch, then as the side 100 sheets extend farther away from the side tubes to prohibit safely closing the space with the brick in this position, I am enabled to close the larger spaces by placing the upper step 18 of the side brick upon the 105 body of the arch, as shown in Fig. 3.

110 Thus it will be seen that where it has been customary even in a single furnace to provide several sizes of side bricks I need but a single form. As already stated the arch also has a large field for service in the different types of locomotives in which the spaces between the side tubes and the side sheets vary at given distances from the flue sheet.

115 Another advantage inherent in my arch is that the key brick carries within itself all the elements necessary to close spaces which vary considerably in width. In other words it is not necessary to provide a special body 120 brick with which to coact. I am, therefore, able to build locomotive arches in locomotives of various types with but two forms of brick, that is, a body form and a side form. The body bricks being all supported in like 125 manner and not requiring any special conformation enables the most economical use of the firebrick. To illustrate this statement consider an arch which requires body bricks of special conformation to coact with 130

the side bricks. Such bricks usually require more material than is necessary in an ordinary body brick which merely extends between two tubes and closes the spaces therebetween. If the brick does not require more material, it is harder to make and, therefore, more expensive. The result of this is that if the body brick are all to be of the one form, the central row which does not coact with the side bricks contain more material than is necessary or is more expensive than is necessary.

I claim—

1. In a locomotive furnace, having a group of arch tubes longitudinally arranged therein and of less width than the firebox, an arch body comprising a plurality of brick resting upon the tubes, in combination with side brick resting upon the side rows of the arch body and extending upwardly therefrom into engagement with the side sheets, the said side bricks having their arch body engaging ends provided with a plurality of notches and thus adapted to rest upon the arch body in a number of different predetermined definite positions in manner to close spaces between the arch body and the side sheets of greatly varying widths.
2. A locomotive furnace having a group of arch tubes longitudinally arranged therein and having side tubes spaced from the side sheets, in combination with an arch body resting upon the tubes and comprising a plurality of substantially identical brick, side brick resting upon the arch body extending upwardly into wedging engagement with the side sheets, the body engaging portion thereof containing a plurality of notches to rest in a plurality of predetermined definite positions on the arch body whereby the side brick is adapted to take a plurality of positions varying in distance from the center of the arch, as and for the purpose specified.
3. In a locomotive furnace, a group of arch tubes of less width than the firebox, in combination with a brick arch arranged

therein and composed of two brick forms, a plurality of one-form of brick resting upon the arch tubes and constituting the arch body and a plurality of the other form of brick resting upon the side of the arch body and extending upwardly and outwardly into engagement with the side sheet, said side bricks having a step-like lower end for engagement with the arch body in a number of definite positions to close spaces between the arch body and the side sheets of greatly varying widths.

4. A side brick for locomotive furnace arches relatively thick at one end, relatively thin at the other end, and tapering therebetween, said thick end having a plurality of longitudinally extending parallel flat surfaces in different planes and a plurality of other longitudinally extending parallel flat surfaces arranged at substantially right angles thereto and extending therebetween.

5. A substantially wedge-shaped side brick of substantially rectangular cross-section, for refractory fire arches, having a plurality of longitudinally arranged steps at the base portion thereof.

6. A side brick for locomotive furnace arches comprising a substantially wedge-shaped body of refractory material rectangular in general cross-section and recessed in one side, the portion adjacent the base being formed with a plurality of longitudinally arranged steps.

7. A side brick for furnace arches, comprising a substantially wedge-shaped body of refractory material rectangular in general cross-section, having a plurality of recesses in one of the largest side portions, and being formed with a plurality of longitudinally arranged steps adjacent its base.

In testimony whereof, I have hereunto set my hand, this 10th day of January, 1913, in the presence of two subscribing witnesses.

CHARLES E. MILLER.
